US0D1000895S

(12) **United States Design Patent** (10) Patent No.: **US D1,000,895 S**
(45) Date of Patent: ** Oct. 10, 2023

(54) **BASE FOR A FOOD PROCESSING APPLIANCE**

(71) Applicant: **BABYLISS FACO SRL**, Wandre (BE)

(72) Inventor: **Sophie Bourgeois**, Liège (BE)

(73) Assignee: **BABYLISS FACO SRL**, Wandre (BE)

(**) Term: **15 Years**

(21) Appl. No.: **35/513,365**

(22) Filed: **Nov. 26, 2021**

(80) **Hague Agreement Data**

Int. Filing Date: **Nov. 26, 2021**

Int. Reg. No.: **DM/218099**

Int. Reg. Date: **Nov. 26, 2021**

Int. Reg. Pub. Date: **Jan. 14, 2022**

(30) **Foreign Application Priority Data**

May 28, 2021 (EM) 008557813-0001

Primary Examiner — Messina L Smith

(57) **CLAIM**

The ornamental design for a base for a food processing appliance, as shown and described.

DESCRIPTION

Figure 1.1 is a top, front, right side perspective view of a base for a food processing appliance showing the new design;

Figure 1.2 is a front view thereof;

Figure 1.3 is a right side view thereof;

Figure 1.4 is a rear view thereof;

Figure 1.5 is a top view thereof;

Figure 1.6 is a bottom view thereof;

Figure 1.7 is a top, rear, left side perspective view thereof; and

Figure 1.8 is a left side view thereof.

In the drawings, the portions shown in broken lines in the color red form no part of the claimed design.

1 Claim, 8 Drawing Sheets
